UNITED STATES PATENT OFFICE.

BURT A. PETERSON, OF ROCKFORD, ILLINOIS, ASSIGNOR TO HOWARD D. COLMAN, LUTHER L. MILLER, AND HARRY A. SEVERSON, COPARTNERS DOING BUSINESS AS BARBER-COLMAN COMPANY, OF ROCKFORD, ILLINOIS.

BOBBIN-HOLDER.

1,101,811.

Specification of Letters Patent. Patented June 30, 1914.

Application filed December 7, 1910. Serial No. 595,988.

To all whom it may concern:

Be it known that I, BURT A. PETERSON, a citizen of the United States, residing at Rockford, in the county of Winnebago and State of Illinois, have invented certain new and useful Improvements in Bobbin-Holders, of which the following is a specification.

This invention relates to bobbin-holders used upon spooling frames and other textile machinery.

The object of this invention is to prevent excessive jumping of the bobbin as the yarn is being unwound, and thereby permit of unwinding the yarn at a higher speed than has heretofore been possible. This object I attain by providing the bobbin-holder with a cushioned or yielding backstop.

In the accompanying drawings Figure 1 is a top plan view of a bobbin-holder embodying the features of my invention. Fig. 2 is a side elevation of said holder as arranged upon a spooling frame. Fig. 3 is a sectional view taken in the plane of dotted line 3—3 of Fig. 2.

I have herein shown my invention as applied to a bobbin-holder of the type illustrated in my application Serial No. 465,391 filed November 30th, 1908, but it will be understood that the present improvements are not limited to use with bobbin-holders of that type.

The embodiment herein represented comprises a bracket 1 which may be provided with any suitable means for securing it in place upon a spooler or other machine, such as a clamping jaw 2 and a set screw 3, A indicating the ordinary supporting bar of a spooler frame. To the upper end of the bracket 1 are fixed two parallel arms 4 which support a loop of flexible material to form a pocket or holder 5 for the bobbin. Said pocket may be formed from oil cloth or other suitable flexible and smooth material. The pocket is open at its forward and rear ends, the bobbin being inserted through the forward end of the pocket. To provide a cushioned or yielding backstop for the bobbin I employ a plate 6 of sheet metal or the like, said plate, in this embodiment, being attached at its upper edge to the upper part

of the bracket 1. The lower edge of the plate is herein shown as bent to lie against the bracket 1 and to space the body of the plate, which is contacted by the bobbin, away from said bracket. The plate 6 is thin enough to yield to the movements of the bobbin and to thereby cushion its end-wise vibrations.

7 are parallel arms fixed to the bracket 1 and constituting a guide for the thread 60 being unwound. The outer ends 7^a of the arms 7 may diverge, as shown in Fig. 1, to form a guide for the insertion of the thread between the arms 7 by the operator.

By reason of the yielding character of the 65 pocket 5 and the backstop an increased speed of the spooling frame is rendered possible.

It will be understood that the construction of the cushioned backstop may be modified in various ways without departing from the 70 spirit of the invention.

I claim as my invention:

1. A bobbin-holder for spooling frames and the like comprising a support upon which a bobbin may lie on its side, and a 75 cushioned backstop.

2. A bobbin-holder for spooling frames and the like comprising a flexible bobbin-supporting loop and a cushioned backstop.

3. A bobbin-holder for spooling frames 80 and the like comprising a bracket, a support on said bracket on which a bobbin may lie on its side, and a flexible sheet-metal backstop mounted on the bracket.

4. A bobbin-holder for spooling frames 85 and the like comprising a bracket, bobbin-supporting means on said bracket, a sheet-metal backstop plate secured at its upper edge to the bracket and adapted to bear at its lower edge against the bracket, the body 90 of the plate being spaced away from the bracket and being in position to be contacted by the butt of a bobbin.

In testimony whereof I affix my signature in presence of two witnesses.

BURT A. PETERSON.
